UNITED STATES PATENT OFFICE.

CHARLES I. CONOVER, OF CHARLESTON FOUR CORNERS, NEW YORK.

DESIGN FOR A BUTTER-RECEPACLE.

SPECIFICATION forming part of Design No. 26,153, dated October 6, 1896.

Application filed August 19, 1896. Serial No. 603,274. Term of patent 7 years.

To all whom it may concern:

Be it known that I, CHARLES I. CONOVER, a citizen of the United States, residing at Charleston Four Corners, in the county of 5 Montgomery and State of New York, have invented and produced a certain new and original Design for a Butter-Receptacle; and I do declare the following to be a full, clear, and exact description of the invention, such as 10 will enable others skilled in the art to which it appertains to make and use the same.

The figure in the drawing represents a retailer's butter-receptacle, showing my design.

The essential feature of my design is the

rectangular receptacle A, having tapering 15 sides a, tapering ends b, and the vertical V-shaped grooves c, arranged in parallel series in the sides and bottom.

What I claim is—

The design for a butter-receptacle, substantially as shown and described.

In testimony whereof I hereunto affix my signature in presence of two witnesses.

CHARLES I. CONOVER.
